ROD DECK SCREEN WITH RUBBER-COVERED CYLINDRICAL CLAMPING MEANS

Ray C. Newhouse, Wauwatosa, Wis., assignor to Allis-Chalmers Manufacturing Company, Milwaukee, Wis., a corporation of Delaware

Application November 3, 1944, Serial No. 561,698

5 Claims. (Cl. 209—395)

1

This invention relates to the construction of parallel rod screen decks for material separation, particularly of the type in which the bars or rods extend longitudinally of the screening surface and are designed to be individually removable for replacement.

It has been found desirable to support the rods in screens of this type intermediate their ends in a manner to spring the rods upwardly so that they tend to remain in a position and tightly pressed against the rod end supports by their own resilience, the ends being seated in sockets in the screen frame.

One of the problems encountered in such screens is the difficulty of replacement of rods due to the necessity of holding the rods in flexed condition while inserting them endwise into their corresponding sockets, and in operation, the sockets tend to become excessively worn and the rods loosened.

It is an object of the present invention to provide an improved rod deck screen structure in which the rod ends may be firmly clamped in position to prevent their becoming loosened by wear.

Another object is to provide such a screen structure in which insertion of the rods is simplified by means providing for the opening of a large slot in the rod end supporting member into which a rod end may be readily inserted and means to clamp the rod firmly in place after insertion.

Still other objects and advantages may appear as described hereinafter with reference to the drawing, in which:

Fig. 1 is a top elevation of a screen according to the invention;

Fig. 2 is a fragmentary longitudinal sectional view on an enlarged scale taken on the line II—II of Fig. 1;

Fig. 3 is a fragmentary front elevation of a portion of the screen of Fig. 1 showing the clamping mechanism on an enlarged scale;

Fig. 4 is a cross-sectional view taken on the line IV—IV of Fig. 2.

The drawing illustrates a preferred embodiment of the invention in which a screen formed on a rectangular, rigid frame having side members 1 and at least one pair of end members 2 and 3 rigidly connected with, and extending transversely between the side members 1. The end members 2 and 3, together with an intermediate transverse member 4 spaced therebetween, which may be called a camber bar, and a movable clamping bar 6, form the supports for

2

a screen surface 7 formed of a plurality of parallel rods 7'.

The end members 2 and 3 may consist of I-beams, channels, or other structural forms, having horizontal ledge portions 8 and 9, respectively, extending towards each other. The ledge 9 of end member 3 may be provided with a removable or integral rod-end engaging wear plate 11 on its under side, having recesses or sockets 11' laterally spaced therein to receive the adjacent ends of parallel rods 7' inserted longitudinally from the direction of end member 2 and passing over intermediate member 4, which has its upper edge above the general level of ledges 8 and 9 and may be provided on its upper edge with a pad 12 of rubber or other durable resilient material and may or may not be provided with laterally spaced grooves 12' for spacing the rods 7'. The end member 2 may have on the under side of its ledge portion 8 a wear plate 13 either integral therewith, or removably attached thereto, having a series of longitudinally extending laterally spaced recesses or sockets such as grooves 13' in its lower surface corresponding to the sockets 11' in wear plate 11, and aligned therewith.

Obviously the sockets 11' and grooves 13' may be formed directly in the ledge portions 8 and 9 of end members 2 and 3. Where plates 11 and 13 are used, however, as shown in the drawing, they are, preferably, removably secured as by bolts 16 to their respective end members 3 and 2 or ledges 9 and 8.

The sockets 11' and grooves 13' form longitudinally aligned, laterally spaced pairs of recesses, sockets or rod end seats adapted to engage the upper surfaces of the ends of rods 7', sprung into place over camber bar 4. The length of rods 7' is sufficiently greater than the distance between ledges 8 and 9 to allow the opposite ends to be caught and retained against upward displacement under the ledges 8 and 9 when inserted and flexed over camber bar 4.

The rods 7' may be formed normally straight, of resilient steel, or other suitable material having an elasticity sufficient to permit shortening by flexion sufficiently to allow insertion of one end under a ledge 8 with the other end inserted under opposing ledge 9. The natural tendency of the flexed rod to resume its normally straight form will cause it to be held firmly in place against intermediate member 4 with its ends firmly pressed upwardly against under surfaces of ledges 8 and 9, or the respective wearing plates 11 and 13.

Mounted transversely between side members 1

of the screen, close to and parallel to a ledge 8 having grooves 13' in its lower surface, is a clamping bar 6, arranged to be movable to and from the under surface of the ledge 8 into and out of engagement with the under surfaces of rods 7', when in place in grooves 13', to clamp the rods firmly against forces tending to displace the ends downwardly, as for example the weight of material being screened, or vibrations of the rods 7'.

Clamping bar 6, according to the invention, may be formed as shown in the drawing, as a hollow cylindrical member having eccentric end-extensions 14 engaged in bearings 15 mounted on side members 1. Actuating mechanism may be any suitable means to angularly rotate the end-extensions 14 and bar 6 about the axis of end-extensions 14, as for example hand bar 17 and ratchet mechanism 18. The bar 6 may be covered with a heavy rubber sleeve 6' which forms a wearing and silencing surface which is selectively rotatable relative to bar 6 for renewal of the actual wearing surface bearing against the rods 7'.

It will be clear that grooves like 13' may be used in place of sockets 11', if a corresponding additional clamping bar 6 (not shown) is employed to engage the corresponding ends of rods 7' under ledge 9.

With clamping bar 6 in released position, the screen surface may be readily formed by inserting the ends of rods 7' in sockets 11', then individually flexing rods 7' to shorten them sufficiently to enable the free ends to be inserted under the opposing ledge 8. The rod ends may be moved laterally to engage the proper seat in a groove 13'. After insertion of all rods 7' clamping bar 6 is moved into clamping engagement with the rod ends by hand bar 17 and retained in clamping relation by ratchet mechanism 18, or other suitable mechanism.

Preferably, steel wearing plates 11 with sockets 11' of limited depth are used at the end of the screen surface 1 towards which material is meant to move over the screen, thus fixing the rods against movement in that direction. This provides an almost indestructible socket at one end, while at the feed end, towards which there is no tendency for the rods 7' to move, the rod ends are receivable in a broad opening slot when the clamp bar 6 is relaxed, and are firmly clamped in spaced relation in grooves 13' when the clamping bar 6 is tightened.

It will be readily understood that this invention provides a simple, durable and easily repaired screen, and that, while specific structure has been described and illustrated, the invention is not limited to the precise structure so described and illustrated, but is intended to include such equivalents as may occur to persons skilled in the art to which it appertains, within the scope of the appended claims.

It is claimed and desired to secure by Letters Patent:

1. A parallel rod material separating screen comprising a rigid rectangular frame, laterally spaced pairs of aligned sockets in opposed faces of a pair of parallel frame members, said sockets having downwardly facing individual rod end receiving seats, a plurality of separate substantially rectilinear spring metal rods each having its extreme ends seated individually in an aligned pair of said sockets, and a clamping bar operatively mounted on said frame adjacent and parallel to one of said socketed frame members for move-

ment into engagement with the lower surfaces of said rods adjacent their ends to clamp said rods upwardly against said seats, whereby said rods are individually held in position in laterally spaced relationship, said clamping bar being tubular in form and having a bar engaging surface selectively rotatable relative to said rods to present a plurality of different portions for actual contact with said rods.

2. A parallel rod material separating screen comprising a rigid rectangular frame, laterally spaced pairs of aligned sockets in opposed faces of a pair of parallel frame members, said sockets having downwardly facing rod end receiving seats, a plurality of substantially rectilinear spring metal rods each having its extreme ends seated in an aligned pair of said sockets, and a clamping bar operatively mounted on said frame adjacent and parallel to one of said socketed frame members for movement into engagement with the lower surfaces of said rods adjacent their ends to clamp said rods upwardly against said seats, said clamping bar being cylindrical in form and having end extensions eccentric thereto journaled in said frame and clamping bar adjusting mechanism on said frame operatively engaging said extensions to move said bar angularly relative to the axis of said extensions in clamping and unclamping relation to said rods.

3. Means for supporting the ends of a plurality of parallel rods in laterally spaced relation comprising a frame, a frame bar having a plurality of laterally spaced parallel grooves in an under surface thereof, a cylindrical clamping bar eccentrically journaled in said frame for angular movement in parallel relation towards and away from said under surface of said frame bar to clamp said rod ends firmly in said grooves and means for holding said clamping bar in clamping relation.

4. Means for supporting the ends of a plurality of parallel rods in laterally spaced relation comprising a frame, a frame bar having a plurality of laterally spaced parallel grooves in an under surface thereof, a cylindrical clamping bar eccentrically journaled in said frame for angular movement in parallel relation towards and away from said under surface of said frame bar to clamp said rod ends firmly in said grooves, said clamping bar having a sleeve like rubber cover thereon and rotatable on the axis of said bar to selectively present different wearing surfaces to said under surface, and means for holding said clamping bar in clamping relation.

5. A parallel rod material separating screen comprising a rigid rectangular frame, laterally spaced pairs of aligned individual rod end receiving sockets in opposed faces of a pair of parallel frame members, said sockets having rod end engaging seat portions generally in the plane of said frame and facing the same side of said plane, a camber bar in said frame parallel to and spaced intermediate said socketed frame members and having a rod supporting surface facing in a direction opposite that in which said seat portions of said sockets face, a plurality of separate generally rectilinear flexible resilient rods each having its opposite ends individually seated in an aligned pair of said sockets and its intermediate portion sprung over said rod supporting surface of said camber bar, the location of said rod supporting surface of said camber bar relative to the plane of said seat portions of said sockets being so chosen with relation to the normal unstressed

60 members, said sockets having rod end engaging seat portions generally in the plane of said frame and facing the same side of said plane, a camber bar in said frame parallel to and spaced intermediate said socketed frame members and having a rod supporting surface facing in a direction opposite that in which said seat portions of said sockets face, a plurality of separate generally rectilinear flexible resilient rods each having its opposite ends individually seated in an aligned pair of said sockets and its intermediate portion sprung over said rod supporting surface of said camber bar, the location of said rod supporting surface of said camber bar relative to the plane of said seat portions of said sockets being so chosen with relation to the normal unstressed

65 70 75

form and thickness of said rods that said rods are somewhat bowed when in position under an elastic stress which tends to retain them in position in parallel laterally spaced relation in said frame, and a clamping bar operably mounted on said frame adjacent and parallel to one of said socketed frame members for movement into engagement with the surfaces of said rods adjacent their ends to clamp said rod ends firmly against said rod end engaging seats of said one of said 10 socketed frame members.
